UNITED STATES PATENT OFFICE.

DARWIN HANAUER, OF LA GRANGE, ILLINOIS, ASSIGNOR TO KINNEY-ROME COMPANY, OF CHICAGO, ILLINOIS, A CORPORATION OF ILLINOIS.

BEDSPRING.

Application filed November 25, 1922. Serial No. 603,171.

The invention relates to spring bed bottoms and more particularly to that type employing a rigid rectangular spring-supporting frame formed of metal bars. Usually such bars, for greater strength and for supporting the spring bottom in a bed frame are provided with side angle bars having outwardly projecting horizontal flanges and vertical depending flanges. The side angle bars are connected at their ends and intermediate their ends by means of transverse spring supporting bars and usually the transverse end members are also formed of angle bars. The present invention seeks to provide an improved bed spring frame which is so constructed that without impairing its strength is devoid of sharp corners. The invention consists in the features of improvement hereinafter set forth, illustrated in the preferred form in the accompanying drawings and more particularly pointed out in the appended claim.

In the drawings:

Fig. 1 is a perspective view of one corner of a bed spring embodying the present improvement;

Fig. 2 is a plan view of one end portion of the bed spring frame, with the springs supported thereby shown in horizontal section;

Fig. 3 is a detail plan view of one corner of the frame;

Fig. 4 is a detail elevation thereof with one of the side bars of the frame shown in vertical section;

Fig. 5 is a view similar to Fig. 4 illustrating a modification;

Fig. 6 is a view similar to Fig. 3 illustrating a further modification; and

Figs. 7 and 8 are detail sections on lines 7-7 and 8-8 respectively of Fig. 6.

As usual the rectangular frame of the bed spring comprises side rails 1, transverse end members 2 and a series of intermediate transverse members 3. Rows of vertical coiled springs 4 are mounted upon the transverse members 2 and 3 and are connected together in any usual or suitable manner and to a border wire 5 having rounded corners, as indicated in Fig. 1. For greater strength and rigidity the side rails 1, and preferably also the end members 2 are formed of angle bars, and preferably, as

shown, the side rails are larger and heavier than the end rails, the side angle bars having 55 depending vertical flanges and the end bars having upwardly projecting vertical flanges upon which the end rows of springs are mounted. The members 3 which carry the intermediate transverse rows of springs are 60 formed as usual of flat metal bars, the ends of which overlap and are riveted to the outwardly projecting horizontal flanges of the side rails 1 and the intermediate portions of which are depressed and arranged in vertical planes. 65

The end angle bars in the improved construction terminate short of the corners of the bed spring frame and the horizontal and vertical flanges at the end portions of 70 the side angle bars 1 are shaped by forging to form rounded corner portions 6 and 7 and inwardly projecting integral extensions 8 and 9 which overlap the ends of the angle bars 2. Preferably also the horizontal 75 flanges 8 of the extensions are cut away or otherwise suitably reduced in width to correspond to the width of the angle bars 2, and are united to the horizontal flanges of the bars 2 preferably by rivets 10, as 80 shown. The vertical flanges of the end angle bars 2 and the vertical flanges 9 of the integral extensions of the side bars 1 are provided, as shown, with rounded end edges 11 and 12. 85

In the form shown in Figs. 1 to 4 inclusive, the inturned ends of the side angle bars extend beneath the ends of the angle bar end members 2. If desired the horizontal flanges of the end members may extend beneath the horizontal flange 8 of the side bar extensions, as shown in Fig. 5, the overlapping horizontal flanges being preferably of such width that they abut against the vertical flanges of the connected bars. The bottom coils of the end row of springs extend through holes 14 formed in the upwardly projecting vertical flanges of the end members. 95

The improved construction provides a 100 spring supporting frame for bed bottoms which is devoid of sharp edges and corners and has instead rounded corners like the top border wire. Furthermore the improved construction materially adds to the strength 105 and rigidity of the frame. Changes may be

made in the details set forth without departure from the essentials of the invention as defined in the claim.

I claim as my invention:

- 5 In a bed spring, the combination of transverse rows of vertical coiled springs having their upper ends connected together and to a border wire, and a main spring-supporting frame comprising side angle bars
10 having outwardly projecting horizontal flanges and depending vertical flanges provided with integral inturned end portions in the same planes as the main portions

thereof and forming rounded frame corners and inwardly projecting extensions, and end 15 angle bars and intermediate cross bars rigidly secured to said side angle bars and carrying the rows of springs, said end angle bars terminating short of the frame corners and having horizontal flanges secured to 20 the horizontal flanges of said extensions and vertical, upwardly projecting spring supporting flanges, substantially as described.

DARWIN HANAUER.
